DESIGN FOR A RAZOR AND BLADE HOLDER

Charles M. Carr, Los Angeles, Calif., assignor to
Modern Plastic Co., Los Angeles, Calif., a cor-
poration of California

Application October 28, 1946, Serial No. 134,349

Term of patent 14 years

(Cl. D4—3)

To all whom it may concern:

Be it known that I, Charles M. Carr, a citizen of the United States, residing at Los Angeles, in the county of Los Angeles and State of California, have invented a new, original, and ornamental Design for Razor and Blade Holder, of which the following is a specification, reference being had to the accompanying drawing, forming part thereof.

Figure 1 is a perspective view of the razor and blade holder embodying my new design;

Fig. 2 is a view in front elevation of the same; and

Fig. 3 is a bottom plan view of the same.

I claim:
The ornamental design for a razor and blade holder, as shown.

CHARLES M. CARR.
